(57) **CLAIM**

The ornamental design for an electrical receptacle adapter, as shown and described.

DESCRIPTION

FIG. 1 is a front elevational view of an electrical receptacle adapter embodying my new design.

FIG. 2 is a top plan view of the electrical receptacle adapter illustrated in FIG. 1.

FIG. 3 is a bottom view of the electrical receptacle adapter illustrated in FIG. 1.

FIG. 4 is a back elevational view of the electrical receptacle adapter illustrated in FIG. 1.

FIG. 5 is a left side elevational view of the electrical receptacle adapter illustrated in FIG. 1; and,

FIG. 6 is a frontal perspective of the electrical receptacle adapter illustrated in FIG. 1.

The broken lines in the drawings are for illustrative purposes only and form no part of the claimed design.
